UNITED STATES PATENT OFFICE.

WILLIAM C. N. SMITH, OF LINCOLN, NEBRASKA, AND ERASTUS ROADIFER,
OF LOGAN, IOWA.

GRAIN-DOOR FOR CARS.

No. 856,663.

Specification of Letters Patent.

Patented June 11, 1907.

Application filed October 22, 1906. Serial No. 340,039.

To all whom it may concern:

Be it known that we, WILLIAM C. N. SMITH, residing in Lincoln, in the county of Lancaster and State of Nebraska, and ERASTUS ROADIFER, residing in Logan, in the county of Harrison and State of Iowa, have jointly invented certain new and useful Improvements in Grain-Doors for Cars, of which the following is a specification, sufficiently clear to enable those skilled in the art to which it appertains to make and use the same.

Our invention relates to grain doors for cars. Its object is:—1. The production of grain doors which will prevent the loss of grain through car doors in shipping. 2. The production of grain tight doors which may be used inside and in connection with the ordinary car door. 3. The production of grain doors which will swing back against the car sides, out of the way, on the outside and also on the inside of the car. 4. The production of grain doors which will swing open and back against the outside of the car or the outside car door without hindrance from obstructions such as fixed pulleys, nineteen inches from the sides of the car, on elevator platforms. 5. The production of permanent and practical grain doors for cars which will do away with the great expense and labor now incurred by rail-roads in nailing up with lumber the inside of car doors for grain shipping and also avoid the damage now being done to the cars by the present practice. 35 6. The production of a grain door for cars which will greatly speed the process of unloading grain at elevators etc., and thereby increase the earning capacity of the cars thus employed. These purposes are attained in 40 my invention by certain novel construction and combination of parts which will be hereinafter described and claimed.

My invention is illustrated in the accompanying drawings.

45 Figure 1, represents a perspective view of my grain doors, open and swung back against the inner sides of the car. Fig. 2, represents a perspective view (from outside the car), of my grain doors shut ready to lock. Fig. 3, represents a plan view of the tongue portion of my hinge. Fig. 4, represents a perspective view of the tongue part. Fig. 5, represents a perspective view of the plate and clips portion of my hinge. Fig. 6,

represents my hinge pin or bolt with clips by 55 which it is attached to grain doors. Fig. 7, represents a door bumper. Fig. 8, represents a horizontal section through the door on line of the hinge.

I preferably make two of my grain doors 60 for each car door way, so as to swing together in the center, their contiguous edges halved together when shut to prevent leakage at the joint, which in conjunction with the fastening bar *i*, forms practically a 65 matched joint. I make each door of two thicknesses of suitable lumber with the grain of the wood in the two sides running at approximately right angles. If desired the inside of each door may be metal lined to 70 protect them from coal or other rough freight.

The hinges are constructed as follows:—A metal strip *b*, is made with holes through which it is screwed or bolted to the side of the car door-way frame. From one side of 75 this strip project two lips each having its bolt hole. The tongue piece *a*, I make of a strip of suitable metal provided with a longitudinal slit extending nearly to one end the other end formed into a round hammer 80 shaped head, provided with a bolt hole through its center, the head part fitting between the two lips on the metal strip *b*, and hinged thereto upon a bolt or rivet. Through the slit in the tongue piece I pass a metal 85 pin, *c*, each end of which I make a **U** shaped clip, in the sides of the clips I make holes through which I bolt or rivet them to the car door for which purpose I notch the door to fit the clips neatly, the space between the 90 clips being just sufficient to allow the tongue piece to slide through freely. I make the inner part of the notch in the door **V** shaped to allow the tongue portion of the hinge the freest motion possible around the hinge pin 95 without leaving any opening for the grain to leak out of.

I bolt to each door a long and strong hook in such position that it will hook securely back to a strong staple or eye provided therefor in the car door-frame near its outer edge. Near the point of the hook I attach a shackle made of several chain links terminating in a bolt by which it is fastened to the grain door so as to hold the grain door solidly against 100 the door frame when the grain doors are closed and the hook is driven through the eye. This arrangement enables one hook to 105

hold both sides of the door securely, and serve the triple purpose of a hook, a brace and a lock. Any wear on the shackles may be taken up by tightening the bur on the 5 shackles bolt as desired. I latch the two doors together by means of the single latch lever *g*, which I bolt so as to swing freely to one door and fit snugly into the catch, *h*, on the other door. I provide the door having the outside 10 projecting edge with an ordinary sliding bolt for fastening the said door by means of a hole provided therefor in the metal sill of the car door way. As may be readily seen these arrangements constitute powerful fastenings 15 for such doors.

I make the doors sufficiently high above the grain line for safety, though they may be made any height which will permit them to freely swing out through the car door way. 20 I make my doors preferably with a metal shoe on the bottom to prevent the bottom of the doors being injured to cause leaks.

In using my doors they are shut, the hooks are forced in the eye and catches respectively 25 and the doors are secured. In unloading the long hooks are driven out of the eyes in the door frames, the lever is driven out of the catch provided therefor and the doors swing outward and open. The construction of the 30 hinges permits the doors to swing around and fold against the inside of the car, or to swing through the doorway to a position against the outside of the car on one side and against the outside car door on the other side, out 35 of the way, and without hindrance from obstructions, like pulleys on elevator platforms, so near to the sides of the car as to prevent the use of ordinary swinging doors.

The practical utility of my invention is at 40 once apparent to those familiar with the present status of grain doors for cars and the great expense incurred each year by railroads in boarding up the car doorways for each shipment of grain, and loss of temporary 45 doors used therefor.

Having thus described my invention, what

I claim as new and desire to secure by Letters Patent, is:—

1. Grain doors for cars consisting of two wooden doors, each provided with means of attaching same to car door frame—and permitting each door to swing freely through the doorway, either to a position against the inside of a car or to a position against the outside thereof, said doors halved together at 55 point of contact with each other when closed and provided with means to resist pressure from grain in car, comprising detachable stays extending from the free edge of each door to the door jamb. 60

2. In grain doors for cars the combination of two wooden doors, means of attaching the doors to car door frame permitting the doors to swing freely around the door frame or to close tightly together, said means composed 65 of a metal tongue piece transversely pivoted to a plate attached to car door-frame, said tongue piece provided with a longitudinal slit, through which slit a pin passes, each pin terminating in **U** shaped clips by which clips 70 the pin is attached to car door in recesses provided therefor, the inner edge of which recesses are made **V** shaped, and means to resist pressure of grain in car and hold doors in position consisting of long heavy hooks each 75 made with a shackle of chain links attached near the hook end, the shackle and the other end of the hook being bolted to car door, the hook end fitting into a screw eye provided therefor in door-frame. 80

In testimony whereof we have signed our names to this specification in the presence of two subscribing witnesses.
